UNITED STATES PATENT OFFICE.

RICHARD F. BERNDT AND PHILIP COLLISCHONN, JR., OF SAN FRANCISCO, CALIFORNIA,
ASSIGNORS TO AUTOMATIC PRINTING DEVICES COMPANY, OF SAN FRANCISCO,
CALIFORNIA, A CORPORATION OF CALIFORNIA.

AUTOMATIC EMBOSSED MACHINE.

Application filed December 1, 1920, Serial No. 427,548. Renewed July 21, 1924.

This invention relates to "process" embossing or engraving by which is meant the production of raised letter effects without the use of steel dies or copper plates.

5 Process engraving or embossing as herein referred to is carried on in the following way: The printed sheet as it comes from the press freshly printed is sprinkled with a powder or compound which adheres and 10 combines with the ink, surplus powder is removed by shaking or tapping the sheet, and thereafter the sheet is placed near a heater to dry, thereby causing the ink and powder to combine and cement together, 15 producing either engraved or embossed effects depending upon the particular powder used. Ordinarily this process is carried on entirely by hand and the object of the present invention is to accomplish these operations by mechanical means.

In carrying out this object we provide a machine, preferably power operated, whereby the sheets are automatically carried one at a time by grippers through a receptacle 25 provided with an automatically operated scoop which deposits the powder lightly and evenly over the printed surface. The grippers are carried by a conveyor over a series of lugs or projections which impart thereto 30 a vibratory movement such as to cause the surplus powder to be shaken off. When the grippers reach the end of their run they automatically release the sheet and the latter is switched on to a delivery conveyor 35 which carries the sheet slowly beneath a heater and deposits the same in a finished state wherever desired.

One form which our invention may assume 40 is exemplified in the following description and illustrated in the accompanying drawings in which—

Fig. 1 shows a side elevation of a machine embodying our invention,

Fig. 2 shows a plan view of the same, 45 Fig. 3 shows a central, vertical, sectional view of the upper portion of the machine,

Fig. 4 shows a plan view of one of the gripping devices,

Fig. 5 shows a vertical, central, sectional 50 view of the feeding mechanism and a gripping device adjacent thereto,

Fig. 6 shows a sectional view of a gripping device in closed position.

Fig. 7 shows a plan view of a portion of the feeding device and gripping device. 55

Fig. 8 shows a vertical, sectional view taken through the powder receptacle and illustrating the powder scoop in one position of its movement.

Figs. 9 and 10 show a similar view illustrating different positions of the powder scoop and its actuating means.

The machine in the form herein illustrated comprises a main frame which includes a base 9 and a superstructure 10. A motor 11 is arranged near the base of the machine and connects by a belt 12 with a pulley 13 journaled on the superstructure. This pulley 13 has its hub or shaft connected by a sprocket chain 14 to a sprocket wheel 15 fixed upon a drive shaft 16 extending entirely across the superstructure. The shaft 16 carries driving sprocket wheels 17 one near each end over which endless conveyor chains 18 operate. From the drive wheels 17 each conveyor chain passes downwardly and beneath an idler wheel 19 and thence forwardly to guide wheels 20 at the front of the machine. Thereafter the course of the conveyor chains is rearwardly beneath the curved guide rails 21 and thence upwardly an appreciable distance to a guide roller 22 at the top of the superstructure from which point the chains extend horizontally to a roller 23 at the rear of the superstructure 85 and thence back to the driving wheels 17.

At suitably spaced intervals on the conveyor chains we arrange a gripping mechanism, best shown in Figs. 4, 5 and 6. Each gripping device includes a cross-web 24 extending between opposite chains and fixed to the links thereof, said cross-web constituting a lower gripping jaw. A second jaw 25 is hinged upon the lower jaw by means of a pin 26 and normally held in engagement 95 with the lower jaw by springs 27. An extension or lug 28 on the hinged end of the movable jaw is adapted to ride upon a cam track 29 at the front of the machine to cause the jaws to be opened to receive a printed sheet from a feeding device.

This feeding device comprises a fixed inclined ledge 30 having a movable shelf-plate 31 at its lower end and normally held by spring means in position to support a sheet 105 of paper. A swinging rod 32 is pivotally

connected to the rear side of the ledge 30 and has a crank arm to co-act with the movable shelf-plate. This rod has its opposite end disposed so as to be acted upon by the gripping device as the latter travels beneath the feeding mechanism. The action of the gripping device will be to raise the co-acting end of the swinging arm and thereby cause the shelf-plate to be retracted, whereupon the sheet of paper falls into place between the gripping jaws, it being understood that the cam track 29 is so positioned as to cause the jaws to be open at this time. In order to position the printed sheet properly within the jaws we arrange a row of pins 33 thereon which limit the depth of entry of the sheet within the jaws.

The conveyor chains 18 carry the gripping device past the cam track 29 thereby allowing the jaws to close upon the sheet. The path of the gripping jaws is now beneath the curved guides 21 which overlie a receptacle 34 in which embossing or engraving powder is contained. To insure a deposit of powder upon the printed sheet we provide a scoop 35 carried on a shaft 36 journalled between supports 37 arranged at opposite sides of the frame. To operate this shaft and scoop in timed relation with the travel of the gripper jaws beneath we provide the mechanism shown in Figs. 8, 9 and 10 consisting of a striker arm 38 on one end of the shaft 36, with which arm a lug or projection 39 on one of the conveyor chains co-acts. This lug is some distance in advance of the gripper jaws and causes the striker arm to be carried from the position shown in Fig. 8 to that shown in Fig. 9 during which movement the scoop picks up a quantity of powder from the receptacle. Thereafter the gripper jaws contact with the striker arm and rock it far enough to cause the scoop to be overturned, as shown in Fig. 10. The powder falling from the scoop will strike the printed sheet carried by the gripper jaws.

Having passed beneath the scoop and having been supplied with powder the sheet remains in the gripper jaws and is carried up the vertical run of the conveyor chains, the gripper jaws coming in contact at this time with a series of lugs or projections 40 which cause vibration of the jaws whereby to shake off the surplus powder. At this time the sheet is held substantially in a vertical plane.

Arriving at the top of the superstructure the sheet is carried over a horizontal course by the gripper jaws, and in this connection we arrange a frictionally driven conveyor 41 over the intermediate portion rollers 22 and 23, the rollers throughout the area occupied by the conveyor 41 being of less diameter than the end portions which carry the chains 18. This conveyor is here shown as being made up of a series of endless coil springs

or tapes but may be otherwise constructed. The slippage occurring in the drive of this conveyor 41 and the smaller diameter of that portion of the rollers over which it operates results in a somewhat slower speed on the average than that of the chain conveyors 18. It is the purpose of the conveyor 41 to support the trailing end of the printed sheet.

Near the end of the horizontal run of the conveyor chains 18 the extension 28 on the movable gripper jaw strikes a cam 48 causing the jaw to open, and inasmuch as the trailing end of the sheet is at this time in contact with the conveyor 41 the slower speed of the latter will cause the sheet to be withdrawn from the open jaws.

Provision must be made for allowing the gripper jaws to pass downwardly on their return circuit whereas the sheets must be shunted on to a delivery conveyor which latter comprises an extension frame 43 hinged to the top of the main frame and supported in extended position by rods 44. An idler roller 45 is journalled in the extension frame towards the outer end thereof, and a drive roller 46 is journalled at the inner end of the extension frame. Over these rollers we arrange a series of endless coil springs or tapes 47 constituting conveyors and being of a construction such as to withstand heat. The drive roller 46 is operated by a pulley 48 connected by a belt 49 with a pulley 50 on the drive shaft 16.

To accomplish the transfer of the printed sheet from the frictionally driven conveyor 41 to the delivery conveyor we arrange a bridging conveyor in the space between the rollers 46 and 23. This bridging conveyor comprises endless tapes or bands 51 operating over the roller 46 at one end and over a roller 52 at the opposite end, said roller 52 being journalled in swinging arms 53 pivotally mounted upon the spindles of the roller 46. The arms 53 are normally held by springs in position where their upper ends will lie close to the roller 23, and a bar 54 is connected to one of the said swinging arms 53 and extends upwardly and forwardly terminating in a cam shaped end 55 which is in a position to co-act with the gripper jaws. When the gripper jaws meet said cam shaped end they cause the swinging arms 53 to be lifted away from the roller 23, thus making room for the gripper jaws to pass between. These swinging arms are immediately returned by spring action so as to intercept the released sheet and carry it over on to the delivery conveyor.

The delivery conveyor is provided with a heating element 56, preferably electrical, which is supported on standards 57 fixed to the extension frame 43. The delivery conveyor is comparatively slow moving and printed and powdered sheets are carried thereby beneath the heating element and the

ink and powder and thereby dried and cemented together. Thereafter the sheets are delivered by the conveyor into stacks at the desired place, by means of a supplemental 5 delivery conveyor 58.

The present machine may be lined up to a press so that the pressman feeds the printed sheets directly from the press into the feeding mechanism of the machine. At a speed 10 equal to that of any printing press the gripper jaws receive each sheet individually from the feeding device. Thereafter the sheet is powdered and dusted thoroughly and the compound is cemented with the ink under a heater. The sheets need not be touched by hand from the time they are placed on the feed platform until they are picked up in a stack at the end of the process.

The present machine eliminates hand 20 powdering and tapping off of the surplus powder and thereby effects an enormous saving of labor and time. Its high speed of production obviates all delays and inconveniences and makes it unnecessary to hold 25 up the press. The manner in which the powder or compound is applied eliminates waste and since the printed sheets need not be touched by hand the stock is kept clean, thus insuring a neat job.

30 Various changes in the construction and arrangement of the several parts herein shown and described may be employed without departing from the spirit of our invention as disclosed in the appended claims.

35 The manner in which we connect the bar 24 to the links of the chain 18 is simple and substantial and consists in providing at each end of the bar 24 a connecting piece 24^a having projections 24^b extending through openings in the side bar of the link and riveted 40 therein, as shown in Fig. 4. The part 24^a is fastened to the bar 24 by bolts or otherwise.

Having thus described our invention 45 what we claim and desire to secure by Letters Patent is:—

1. In a device for producing process embossing and engraving comprising means to grip a printed sheet, means to deposit powder thereon, said gripping means being movable to bring the sheet into a substantially vertical plane, and means to vibrate the gripper whereby to shake surplus powder off the sheet.

55 2. In a device for producing process embossing and engraving comprising means to grip a printed sheet, means for feeding sheets to the gripping means one at a time, means for depositing powder on the sheet 60 while the latter is retained by the gripper, means to move the gripper into a position where the sheet will occupy a substantially vertical plane, and means for agitating the gripper whereby to remove surplus powder.

65 3. In a device for producing process em-

bossing and engraving comprising a conveyor, a gripping device arranged thereon, means to feed printed sheets one at a time to the gripping device, a powder retaining device past which the gripping device is moved, means actuated in timed relation with the gripping device to deposit the powder upon the retained sheet and means for imparting vibratory movement to the gripper whereby to shake off surplus powder. 70 75

4. In a device for producing process embossing and engraving comprising a conveyor, a gripping device arranged thereon, means to feed printed sheets one at a time to the gripping device, a powder retaining device past which the gripping device is moved, means actuated in timed relation with the gripping device to deposit the powder upon the retained sheet, means for imparting vibratory movement to the gripper whereby to shake off surplus powder, 80 means for releasing the sheet from the gripping device and a delivery conveyor cooperating with the gripping device to receive the released sheet. 85 90

5. In a device for producing process embossing and engraving comprising a conveyor, a gripping device arranged thereon, means to feed printed sheets one at a time to the gripping device, a powder retaining device past which the gripping device is moved, means actuated in timed relation with the gripping device to deposit the powder upon the retained sheet, means for imparting vibratory movement to the gripper whereby to shake off surplus powder, 95 means for releasing the sheet from the gripping device, a delivery conveyor cooperating with the gripping device to receive the released sheet and a heater overlying the delivery conveyor. 100 105

6. In a machine of the character described a powder receptacle, a rotatable scoop adapted to remove powder from said receptacle and deposit powder on a printed sheet, a 110 conveyor movable past said powder depositing means and means on the conveyor for receiving and retaining the printed sheet.

7. In a machine of the character described a rotatable scoop for depositing powder on a printed sheet, a conveyor movable past said powder depositing means, means on the conveyor for receiving and retaining the printed sheet and means carried by the conveyor for actuating said powder depositing means at the time when the printed sheet is in position to receive the powder. 115 120

8. In a machine of the character described powder depositing means, a conveyor movable past said powder depositing means, means on the conveyor for receiving and retaining the printed sheet, means carried by the conveyor for actuating said powder depositing means at the time when the printed sheet is in position to receive the powder and 125 130

- means over which the conveyor moves to impart a vibratory motion thereto for the purpose of removing surplus powder from the sheet.
- 5 9: In a machine of the character described a powder receptacle, a rotary scoop operating thereon, a carrier movable between the receptacle and scoop, means on the carrier to receive and retain a printed sheet and 45 means on the carrier to rotate the scoop to cause it to move through the receptacle, pick up a quantity of powder therefrom and deposit the same on the printed sheet.
- 10 10. In a machine of the character described a carrier means thereon to receive and retain a printed sheet, and means to apply powder thereto and means cooperating with the sheet retaining means to impart vibratory movement thereto.
- 15 11. In a machine of the character described an endless carrier having a portion of its run substantially vertical, means on the carrier to receive and retain a printed and powdered sheet and a series of lugs or 50 projections arranged on the vertical run of said carrier to impart vibratory movements to the sheet retaining means.
- 20 12. In a machine of the character described an endless carrier, a pair of gripping jaws thereon to receive and retain a printed sheet, means to apply powder to the printed sheet, a delivery conveyor arranged at one 55 end of the carrier, means to cause the gripping jaws to release the sheet near the end of the run of the carrier, means to transfer the sheet from the gripping jaws to the delivery conveyor, said transfer means including a pivotally mounted conveyor arranged between the carrier and delivery conveyor and normally bridging the space between and means actuated by the sheet retaining 60 means to shift said pivotally mounted conveyor and allow the sheet retaining means to pass thereunder, and means to cause the pivotally mounted conveyor to be retracted in time to intercept the previously released sheet.
- 25 13. In a machine of the character described, a conveyer, a sheet-gripping device carried thereby, a powder-containing receptacle over which the conveyer moves, a rotatable scoop arranged over the powder-containing receptacle for removing powder from the container and depositing it upon the sheet and means carried by the conveyer for actuating said rotatable scoop.
- 30 14. In a machine of the character described, a tiltable container for powder, means for conducting a printed sheet past the container, and means set into operation by the movement of the sheet conducting means for tilting the container.
- 35 15. In a machine of the character described a powder receptacle, a rotatable powder scoop adapted to remove powder from said receptacle, and means for conducting a printed sheet beneath the scoop.
- 40 16. In a machine of the character described, a rotatable powder scoop, means for conducting a printed sheet beneath the scoop and means set into operation by the movement of the sheet conducting means for rotating the scoop.
- 45 17. In a machine of the class described, a powdering mechanism, comprising a scoop movable to pick up powder and to dump it, means for revolving the scoop so that it performs these functions in succession during a revolution and means for carrying a sheet to be treated along with the scoop.
